UNITED STATES PATENT OFFICE.

THOMAS J. WATSON, OF BRIDGETOWN, VIRGINIA.

DESIGN FOR A BOX OR CRATE FASTENER.

SPECIFICATION forming part of Design No. 32,039, dated December 26, 1899.

Application filed November 29, 1899. Serial No. 738,731. Term of patent 7 years.

To all whom it may concern:

Be it known that I, THOMAS J. WATSON, a citizen of the United States, residing at Bridgetown, in the county of Northampton and State 5 of Virginia, have invented and produced a certain new and original Design for Box or Crate Fasteners; and I do declare the following to be a full, clear, and exact description of the invention, such as will enable others skilled in the 10 art to which it appertains to make and use the same.

The invention relates to a new and original design for a box or crate fastener; and it consists of a design of the configuration shown in 15 the accompanying drawings, in which—

Figure 1 is a perspective view of the fastener. Fig. 2 is a side elevation. Fig. 3 is a top plan view.

The leading feature of the design comprises the semicircular plate 1, having a bulge 2, 20 from which projects downwardly a cylindrical portion 3, terminating in the laterally-projecting portion 4, which projects parallel with the straight edge of the semicircular plate.

What I claim is—

The design for a box or crate fastener, as herein shown and described.

In testimony whereof I have hereunto set my hand in presence of two subscribing witnesses.

THOMAS J. WATSON.

Witnesses:

THOMAS TRUITT,
R. L. WILLIAMS.
